UNITED STATES PATENT OFFICE.

JOSEPH STOREY TILLING AND HENRY DOBBINS, OF WARRINGTON, ENGLAND.

APPARATUS FOR TURNING HANDLES FROM ROUND STOCK.

1,415,416.

Specification of Letters Patent.

Patented May 9, 1922.

Application filed May 17, 1921. Serial No. 470,303.

To all whom it may concern:

Be it known that we, JOSEPH STOREY TILLING and HENRY DOBBINS, subjects of the King of Great Britain, both residing at 5 Warrington, in the county of Lancaster and Kingdom of England, have invented certain new and useful Improvements in Apparatus for Turning Handles from Round Stock, of which the following is a specification.

10 This invention has for its object a method of and apparatus for turning the handles of brooms, brushes, garden tools and other goods turned from round stock.

In the turning of the handles of brooms 15 and the like these are generally done by hand or by a templet machine, which usually turns the whole handle. This is an expensive way of doing it.

Now our invention consists in turning the 20 handle and at a single operation.

This is best described by aid of the accompanying drawings, in which:—

Figure 1 is a plan view.

Figure 2 vertical end elevation with certain parts removed for clearness, and 25

Figure 3 side elevation of the machine.

In these, A is the specially shaped steel 30 tool, and B is the stock or piece of timber from which the handle is cut. It is shown in the drawings with the handle proper just turned. D is the driving shaft, and D' the pulley which may be fast and loose, but it is shown in the drawings as a wide pulley receiving a belt from a fast and loose pulley 35 on a countershaft. E is roller chain gear connecting the driving shaft D and the other shaft D², F F pedestals carrying shaft D and D², G bracket carrying socket H, I stop pin acting on the piece of timber to be turned 40 at the cutting end, and it will be seen from the drawings Figure 3 that we arrange the stop to act below the centre so as to be clear of the cutting tool A, K pressure roller which is free to revolve on the shaft U supported in the combination fork bracket and levers L. The pressure roller K is normally held in "off" position by the counterweight M but can be pressed down by the treadle N acting on the rod N' and helical spring O. P is a link connecting treadle levers Q and Q² with the knife A, which is free to slide 45 in a guide bracket A'. The knife A is normally counterbalanced by the counterweight

S'. The treadle levers Q and Q² have toggle joints Q' which allow for the extra upward movement required by the presser roller K 55 so as to allow for easy insertion and removal of the stock B. The treadle levers Q and Q² are pivoted on the shaft T² (which also acts as a stay bolt for the wood frame W) and 60 are kept in position by loose collars V. The shafts D and D² carry the rollers X. The knife is secured to the slide rest A' by studs T and four adjusting pins T' are provided. The slide rest A' is carried by the bracket 65 Y which is bolted to the frame. This bracket also has an eye bearing Y' which carries the shaft Y² and Y³ is the other bracket with an eye bearing. R R R are adjustable collars to form stops. 70

The mode of action is as follows:—The piece of timber B to be turned is placed between the socket H and the stops I, resting on rollers X. The machine is set in motion, the attendant presses down the treadle N, 75 thus pressing the roller K on to the piece B before the knife A is moved. This is effected by the lost motion provided by the toggle joint. By further pressure on the treadle the knife A moves down to the piece 80 B cutting same at one steady stroke so as to form a complete handle thereon. The treadle is now released and the counterweights M and S return the knife A and the presser roller K into their "off" positions. 85 The piece B is removed and another piece B inserted, and so on. Z is a gantree and W framing.

We declare that what we claim is:—

1. In a lathe for successively shaping and detaching articles from the end of a round rod, comprising a pair of rotating rollers upon which the rod rests with one end thereof projecting beyond the rollers to the length of the desired article, a pattern knife having 90 a travel towards such projecting portion of the rod, a roller movable towards and from the rod when mounted between the above mentioned pair of rollers and common means for depressing said roller into contact with 100 the rod and for moving the knife into engagement with the projecting part thereof.
2. In combination with a lathe substantially as described in claim 1, the common means for depressing the roller into contact 105 with the rod and for moving the knife into

engagement with the projecting part thereof
yieldingly connected to the roller permitting
the further operation of the said com-
mon means to further depress the knife after
5 the roller has entered into engagement with
the work.

In witness whereof, we have hereunto
signed our names this 26th day of April,

1921, in the presence of two subscribing wit-
nesses.

JOSEPH STOREY TILLING.
HENRY DOBBINS.
